UNITED STATES PATENT OFFICE.

ERNEST R. WENDEMUTH, OF GLEN RIDGE, NEW JERSEY.

FOOT MUFF.

Application filed September 16, 1927. Serial No. 219,948.

My invention relates to foot muffs, and more particularly to foot muffs embodying therein means facilitating the adjustment of the muff to the feet and legs of the wearer.

Heretofore, and for many years past, there have been manufactured and sold, foot muffs of the general type to which my invention relates. Such muffs have had a lining of fur of various kinds, according to the supply and 10 cheapness of different furs, this lining having had a decorative cover, the materials used for which included soft leather, cloth, fur or other materials, to meet the taste requirements of the users. Ordinarily, a top edging 15 of fancy fur was used to finish the upper part of the muff. The sole of the muff was usually of soft leather, although fabrics were sometimes used for this purpose. At different times in the past, the height of these muffs 20 has varied, but their general construction and mode of manufacture has always been the same.

In producing foot muffs of the type above referred to, the usual practice followed has 25 been to first make the lining, "fur side inside, skin side outside", this lining being made of similar side panels, a sole, a more or less straight back and a front, the sides and front being so shaped as to roughly conform to the 30 feet of the wearer. These parts were united by stitching, and the cover and sole then formed of similarly patterned and united parts of slightly larger dimensions, except as to height. The lining was then slipped 35 within the cover, and the two united by means of a decorative top secured by stitching to the upper edges of both the lining and the cover.

In some instances for adjusting the muff 40 to the wearer, ordinary frogs or metallic hooks and eyes were secured near the top of the upper at a point substantially midway between the sides of the muff so that the wearer could draw the back and front together and fasten them in a manner to hold 45 the upper in position about the legs of the user after the feet had been inserted therein. It will be understood that all foot muffs of the type to which I have referred, were adapted 50 to receive both feet of the wearer.

A foot muff embodying my invention possesses all of the characteristics, and is patterned and assembled in the same manner as the old and well known foot muffs above referred to, with the exception that frogs or 55 hooks and eyes are not used to draw the

medial point of the top of the back and front of the muff together, means being provided whereby this top is yieldingly held with a medial contraction, thus not only causing the 60 automatic adjustment of this top about the legs of the wearer, but supporting the top in a manner to permit both feet to be conveniently slipped within the muff without the necessity for drawing the top up about the 65 legs.

While the features above referred to result from the use of a resilient member closely adjacent the top of the muff, this member also serves to normally distend the top in 70 what may be termed "its closed form", and has also been found to prevent the top from collapsing while it is not in use, thus normally holding the top of the muff so that the feet may be readily inserted thereinto. 75

The invention consists primarily in a foot muff embodying therein, the combination with a lining and an exterior decorative cover shaped to receive both feet of a wearer, of a resilient loop contracted medially of the sides 80 thereof and supported adjacent the top of the muff, whereby said top will be held in a normally distended position at opposite sides of the medial contraction of said loop, and normally contracted adjacent said medial contraction, and the open top of the muff will yield, to permit the insertion of the feet through the top thereof, and thereafter automatically close about the legs of the wearer; and in such other novel features of construction and combination of parts as are herein- 85 after set forth and described, and more particularly pointed out in the claims hereto appended. 90

Referring to the drawings, 95
Fig. 1 is a perspective view of a foot muff embodying the invention;

Fig. 2 is a side view thereof; 100
Fig. 3 is a vertical section on the line 3—3 of Fig. 1; and

Fig. 4 is a detail plan view of the resilient member separated from the muff structure.

Like letters refer to like parts throughout the several views.

In the embodiment of my invention shown 105 in the drawings, the lining *a* and the cover *b* of the muff are made with the usual shaped sides, and front, back and sole united by stitching in the usual manner. The lining is made of sheepskin and the cover *b* is made of 110 pile fabric as is the top trim or edging *c*. Following the practices of the prior art of

many years the material used in the lining, cover and top trim or edging may vary as desired, to meet the requirement of the user. It is now the common practice, however, to 5 use fabrics of various shades or tones, so that a fastidious user may secure a foot muff which will harmonize with the color scheme of the upholstery of an automobile and with fancy lap robes.

10 The cutting of the parts of the lining, the top trim or edging and the cover, and their arrangement, follow the practices of the prior art, the lining extending to a greater height than the cover, and the top trim or edging 15 being formed of a strip folded upon itself, one side of the fold lapping the lining, and the other side thereof meeting the top edge of the cover, the lining, the cover and this edging being secured by stitching through 20 both sides of the folded trim or edging, the top of the cover and through the lining below the top thereof. The outer sole shown at *d* is usually of fabric or soft leather, and the inner sole shown at *e* is of sheepskin. The lining and the inner sole have the fur side presented inwardly of the muff in the usual manner.

25 The above characteristics in a foot muff are old and well known in the art, and I make no 30 claim of invention thereto, such having been manufactured and sold for many years past.

In foot muffs made as above described, the upper or leg portion of the muff possesses so little rigidity that when not in use it will collapse at a point immediately above the foot portion, the entire top falling forwardly upon the foot portion. This condition makes it necessary for the wearer to bend over, raise and distend the top by hand 40 when inserting the feet into the muff. Furthermore, even when the feet of the wearer were in a muff, there was a tendency of the front portion of the top to fall downwardly to a certain extent, thus failing to 45 protect the leg immediately above the ankles.

To obviate this condition, I assemble in the top structure a resilient looped member *f* formed of flat spring wire. This looped member is contracted medially of the sides 50 thereof at *g*, so as to form two distended portions *h* and *i* at opposite sides of this contracted portion. The ends of the metal strip forming the loop, preferably are not connected in any way, with the two-fold object of 55 facilitating the expansion of the loop when the feet of a wearer are being inserted in the muff, and to accommodate loops of the same dimension to muffs of varying dimensions at the top thereof. The ends of the strip are 60 indicated at *j* and *k*. In producing the muff, this looped resilient member *f* is stitched to the skin side of the lining adjacent the top thereof, with the ends *j*—*k* lapping, if necessary. It is quite immaterial whether these 65 ends overlap each other, abut or are spaced

apart. In thus assembling the looped member in the top structure of the muffs, the flat of the wire is positioned against the skin of the lining.

When the looped member *f* is properly 70 positioned, the top trim or edging *c* is assembled in the muff structure, thus inclosing and concealing the looped member. When this top trim or edging is once secured in place, it is quite immaterial whether the stitching 75 securing the member *f* in position is broken or not, since it will be held in place by the top trim or edging.

When a muff embodying my invention is 80 not in use, the member *f* will prevent the upper or leg portion of the muff from collapsing upon the foot portion, and if this top is 85 forcibly folded down upon the foot portion, the action of the member *f* is such as to immediately restore the top to its upright position. This is probably due to the fact that the bending forward of the top is accompanied by torsional stresses upon the member *f* sufficient to move the entire top upwardly.

When the feet are inserted one at a time 90 within the muff, the member *f* will yield readily to permit the distension of the top at any point thereof, from the normal shaping 95 thereof by the member *f*, and thus permit the feet to be inserted one at a time through the open top which will immediately assume its 100 normal position when both feet are within the muff. The contracted portion *g* of the member *f* will have the effect of drawing the top of the muff fairly closely about both legs of the wearer, particularly in view of the 105 heavy fleece lining. Of course, if desired, the wearer may use the hands for holding the muff when inserting the feet therein, but when the feet are once inserted it is not necessary to draw and fasten the top of the muff about the legs, since the member *f* will maintain the normal configuration of the entire upper portion of the muff both while the muff 110 is empty and while the feet are therein.

While in actual practice I use a flat wire of 115 approximately one-half inch in width, it is not my intention to limit the invention to the use of such a wire, nor to a single wire. A wire member, however, is highly desirable, 120 since these foot muffs have long life, and there is no deterioration of this member. The use of elastics is prohibitive, first because such material is shortlived, and second because such material cannot give the desired form to the upper portion of the muff.

As stated above, the materials used for the lining, cover or soles of the muff are immaterial, such being a matter of selection. Furthermore, if desired, piping, monograms or other decorative matter may be incorporated in the foot muff according to changing styles or whims of the users.

It is not my intention to limit the invention 125 to the precise details of construction 130

shown in the accompanying drawings, it being apparent that such may be varied without departing from the spirit and scope of the invention.

5 Having described the invention, what I claim as new and desire to have protected by Letters Patent, is:—

1. A foot muff embodying therein, the combination with a lining and an exterior 10 decorative cover shaped to receive both feet of a wearer, of a resilient loop contracted medially of the sides thereof and supported adjacent the top of the muff, whereby said top will be held in a normally distended position at opposite sides of the medial contraction of said loop, and normally contracted 15 adjacent said medial contraction, and the open top of the muff will yield to permit the insertion of the feet through the top 20 thereof, and thereafter automatically close about the legs of the wearer.

2. A foot muff embodying therein, the combination with a lining, an exterior decorative cover shaped to receive both feet of 25 a wearer, and a folded top edging extending about the upper edge of said lining and said cover, of a spring metal loop within said folded top edging, said loop being contracted medially of the sides thereof and supported 30 adjacent the top of the muff, whereby said

top will be held in a normally distended position at opposite sides of the medial contraction of said loop, and normally contracted adjacent said medial contraction, and the open top of the muff will yield to permit 35 the insertion of the feet through the top thereof, and thereafter automatically close about the legs of the wearer.

3. A foot muff embodying therein, the combination with a lining, an exterior decorative cover shaped to receive both feet of a wearer, and a folded top edging extending about the upper edge of said lining and said cover, of a spring metal loop within said folded top edging, said loop being contracted 40 medially of the sides thereof and supported adjacent the top of the muff, the metal of said loop having unconnected ends, whereby said top will be held in a normally distended position at opposite sides of the medial 45 contraction of said loop, and normally contracted adjacent said medial contraction, and the open top of the muff will yield to permit the insertion of the feet through the top thereof, and thereafter automatically close about 50 the legs of the wearer.

In witness whereof I have hereunto affixed my signature, this 14th day of September, 1927.

ERNEST R. WENDEMUTH.
